US0D1088193S

(12) **United States Design Patent** (10) **Patent No.:** **US D1,088,193 S**
(45) **Date of Patent:** **** Aug. 12, 2025**

(54) **SINK STRAINER AND STOPPER**

(71) Applicant: **Jinyu Zheng**, Yongzhou (CN)

(72) Inventor: **Jinyu Zheng**, Yongzhou (CN)

(**) Term: **15 Years**

(21) Appl. No.: **29/987,581**

(22) Filed: **Jan. 24, 2025**

(51) LOC (15) Cl. **23-01**

(52) U.S. Cl.

USPC **D23/261**; D23/259

(58) **Field of Classification Search**

USPC D23/202, 259–263, 203–206, 209, 213, D23/226, 229, 233, 249, 255, 264,

D23/266–269, 389–387, 386–387

CPC .. A47K 1/14; E03C 1/26; E03C 1/264; E03C 1/282; E03C 1/2302; E03C 1/2306

See application file for complete search history.

(57) **CLAIM**

The ornamental design for a sink strainer and stopper as shown and described.

DESCRIPTION

FIG. 1 is a perspective view of a sink strainer and stopper showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The evenly spaced broken lines depict portions of the sink strainer and stopper that form no part of claimed design.

1 Claim, 8 Drawing Sheets
